CLAIM

The ornamental design for a buckle member for bags, as shown and described.

DESCRIPTION

FIG. 1 is a perspective view of a buckle member for bags, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken along line 8-8 in FIG. 2; and,

FIG. 9 is a perspective view of the buckle member for bags shown in an exemplary embodiment.

The broken lines in the drawings are directed to environmental matter and form no part of the claimed design.
